UNITED STATES PATENT OFFICE

FREDERICK A. KOLB, OF NEWARK, NEW JERSEY, ASSIGNOR TO GEISMAN, MUSLINOR & BRIGHTMAN, INC., OF NEW YORK, N. Y., A CORPORATION OF NEW YORK

DESIGN FOR LEATHER OR SIMILAR ARTICLE

Application filed December 26, 1928. Serial No. 29,414. Term of patent 7 years.

To all whom it may concern:

Be it known that I, FREDERICK A. KOLB, a citizen of the United States, and a resident of the city of Newark, in the county of Essex and State of New Jersey, have invented a new, original, and ornamental Design for Leather or Similar Article, of which the following is a specification.

Reference is had to the accompanying drawings forming part thereof, wherein

The figure is a plan view of a swatch of leather showing my new design, the arrows indicating one repeat.

I claim:

The ornamental design for leather or similar article substantially as shown and described.

Signed at New York in the county of New York and State of New York this 22d day of December, A. D. 1928.

FREDERICK A. KOLB.
